(57) **CLAIM**

The ornamental design for an integrated hopper, as shown and described.

DESCRIPTION

FIG. 1 is a top view of the integrated hopper design; FIG. 2 is a left side view of the design of FIG. 1; FIG. 3 is a front view of the design of FIG. 1; FIG. 4 is a right side view of the design of FIG. 1; FIG. 5 is a back view of the design of FIG. 1; FIG. 6 is a bottom view of the design of FIG. 1; and, FIG. 7 is an environmental view of the design of FIG. 1 mounted in the paintball marker body with the hopper lid in an open position showing the internal structure visible from the exterior of the hopper.

The broken lines are for illustrative purposes only and form no part of the claimed design.
